UNITED STATES PATENT OFFICE.

MOYES J. MURPHY, OF SAN LEANDRO, CALIFORNIA.

FUEL-REGULATING APPARATUS FOR EXPLOSION ENGINES.

Application filed May 22, 1922, Serial No. 562,722. Renewed November 1, 1926.

This invention relates to a fuel regulating apparatus for internal combustion engines, and its object is to provide means whereby the fuel may be supplied to the engine at a sufficiently high pressure to effectually atomize it and to supply it in the proper time and quantity to run the engine most efficiently.

Another object of the invention is to provide means whereby the fuel will be injected into the engine during the period of most rapid movement of the fuel pump piston rod, thereby insuring the supply to the engine cylinder of the fuel at the greatest possible velocity and throughout any desired period, the regulating apparatus being arranged to release the pump pressure whenever a given speed is exceeded, thereby maintaining the proper regulation of the engine.

Another object of the invention is to provide means whereby the fuel to be forced to the engine cylinder will be by-passed back to the oil supply tank if the fuel spray nozzle becomes clogged.

Another object of the invention is to provide a simple form of valve for the pump which will be easily operated during the movement of the regulating apparatus.

Another object of the invention is to so arrange the governor weights with respect to the arms supporting them as to dispense with springs and thereby improve the regulation of the engine.

Another object of the invention is to provide means whereby the time of cut off and admission of the fuel to the chamber of the explosion engine may be nicely regulated.

Other objects of the invention will appear as the description proceeds.

An embodiment of the invention is shown in the accompanying drawings in which the same reference numeral is applied to the same portion throughout, but I am aware that there may be modifications thereof.

Fig. 1 is a vertical sectional view of the complete regulating apparatus.

Fig. 2 is a side view of the admission regulator.

Fig. 2^a is a section on line 2—2 of Figure 2.

Fig. 3 is a sectional view illustrating the inlet valve and cams for operating it.

Fig. 4 is a sectional view in plan on a

larger scale than Figure 2 of the admission regulator. 55

Fig. 5 is a vertical section of the inlet nozzle and associated parts.

Fig. 5^a is a section on line 5^a—5^a of Figure 5.

Fig. 6 is a view in elevation of the nozzle and its supporting base. 60

Fig. 7 is a sectional plan view of the nozzle holding base.

Fig. 8 is a development of a portion of the fuel feed cam. 65

Fig. 9 is a plan view illustrating the application of the regulating apparatus to a three cylinder engine, and

Fig. 10 is a plan view of the upper part of the apparatus showing the operation of the regulator weights. 70

The regulator is constructed on a base 1 which has a flange 2 holding a ball bearing 3, and a tube 4 carrying a ball bearing 5. This base is secured to any suitable part 75 of the engine by means of clamps 6 and 7 in such a position that the shaft 8 may be easily driven from the cam shaft of the engine in the proper time, as, for example, with the gears 9 and 10, the latter on a 80 properly timed shaft 11.

The shaft 11 extends upwardly through a casing 12 which rests on top of the casing 1, and which has a ball bearing 13 for said shaft in its upper portion. The casing 12 85 is enlarged at 14 to provide the necessary space to receive the three pump blocks 15, 16, 17, and in order to completely enclose the weights 18 and 19 there is a cover 20 which fits down on the top of the casing 14, 90 and it also forms a support for the bushing 21 which has two ears 22, 23 forming bearings for the shaft 24 on which the regulating gear 25 is mounted.

The regulating gear 25 is in mesh with a 95 series of circular teeth on the upper end of a sleeve 26. This sleeve 26 is slideable on the reduced upper end of the shaft 8 and it has an arm 27 rigidly connected thereto which arm carries a depending pin 28. The sleeve 26 also has two arms 27', 27'' connected thereto which are in turn connected to two links 40, 41 pivotally connected at their other ends to the bell crank arms 37, 38. 100

The shaft 24 is rotated by the hand wheel 105

24', which wheel has several spokes one of which is threaded to receive a nut 24^a which bears on a shoe 24^b in turn bearing on the ear 22 to hold the sleeve 26 frictionally in a given adjustment.

The bell cranks 37, 38 are pivotally mounted on the ends of the four arms 31 to 34 carried by the hub 31^a. The hub 31^a also has four depending arms 31' to 34', which arms 10 support the spiral gears 50, 51.

The upper ends of the two bell cranks 37, 38 are connected to the arms 42 *a*, *b*, *c*, *d*, by pins 43, 43' which arms are joined and enlarged to make the weights at their outer 15 ends.

The shaft supporting the spiral gear 50 has an arm 50^a connected by the link 50^b to the arm 42^a, while the shaft supporting the gear 51 has an arm 51^a connected by a link 20 51^b to the weight arm 42^d.

The length of the levers 37, 38 and links 50^b, 51^b is such that when the weights are down, as shown in Figure 1, that the pivot pins in the upper ends of said links will be 25 aligned with the axis of pins at the angle of the bell cranks 37, 38, the object being to increase or decrease, at will, by the operation of the wheel 24 the angle through which the weights must rise to regulate the engine 30 speed.

Figure 1 shows the high speed position of the arms 37, 38. This regulation insures the proper return of the weights at all speeds, since if the speed is high the weight movement is through a steep angle at the center 35 of gravity of the weights, while if the speed is to be regulated low, the weight may move outwardly through a flatter angle, but which increases in steepness rapidly after the 40 proper point of given regulation is passed.

The spiral gears 50, 51 are in mesh with corresponding teeth of the cut off cam sleeve 52, said sleeve riding on and being revoluble with respect to the admission cam sleeve 53.

45 The cams for momentarily closing the inlet fuel valve are cut on the flanges 54, 55 and lie adjacent one another. These sleeves are in turn both supported by and revoluble with the shaft 8.

50 Adjacent the bearing 3 the shaft 8 has the cam 56. This cam is arranged with a sharp rise 57 and with a regular curve from the top to the bottom of said rise to permit the plungers to return slowly to insure filling the 55 oil pump plunger chamber.

The admission cam sleeve 53 is operated by an arm 53' secured to said sleeve by a bolt 58 and the sleeve is rotated by the pin 28 passing through said arm and contacting with the set screw 59 and spring 60, the latter held in a hole in the arm 53' by the plug 61.

60 The oil pump proper consists of a block such as 16 with a depending nipple 62 secured to the casing 14 by the nut 63. This 65 nipple also serves to support the packing

gland 64'. The pump block has a horizontal hole to receive two bushings 64, 65. These two bushings receive a plunger 66, said plunger being larger in diameter at one end than at the other, the larger end having a 70 central bore to allow the oil to pass therethrough to the port 67, and to the space between the two bushings whenever the valve has its flange 68 off its seat.

The bushing 64 is held in place by the 75 screw plug 69 to which the oil supply pipe is connected. A spring 70 holds the plunger 66 against its operating set screw 71.

The set screw 71 is carried by a lever 72 and a lock nut 73 holds the set screw in any 80 given adjustment. The lever 72 is supported on a pivot pin 74 carried by a bracket 75 secured on the side of the pump block 15.

Extending upwardly from the plunger 66 is the discharge passage closed by the screw 85 plug 76 and connected to the fuel pipe 77 by the union plug 78. A ball 79 is placed in the discharge to prevent the oil from backing out of the oil supply pipe when the pump is being operated. It will be understood that 90 the description of the pump applies to each of the blocks 15 to 17.

The pump plunger 80 extends into the block 15 and is packed by the gland 64'. The plunger 80 is operated by the cross head 81 to which it is connected and which cross head has a pin 82 and ball bearing 83, said bearing being normally held down on the cam 56 by the spiral spring 84.

The oil supply pipe extends from the oil 100 pump to the nozzle support 90 and is connected thereto by the union 91. The nozzle consists of a tube 92 having a nozzle tip 93 secured thereto by the threaded sleeve 94. The nozzle valve consists of a long pin 95 seated at its lower end in the nozzle 93 and extending through a bushing 96, said bushing being screwed into the top of the tube 92. The tube 92 extends through the support 90 and is rigidly secured thereto by the 110 threaded cap 97, which cap also serves to hold the spring 98 which determines the pressure required to lift the valve 95. It will be seen that the upper end of the valve stem is larger than the lower end and it is lapped 115 to fit the bushing 96 and is provided with a series of grooves to prevent leakage.

A strut 99 rests on the top of the valve and slides on the lower end of a set screw 100, the spring 98 bearing on a flange on the lower 120 end of the strut 99. The screw 100 is locked in place by the nut 101. The object of the set screw is to allow the valve 95 to rise not more than a small fraction of an inch and to prevent it from being blown out by the tremendously high pressure (5000 to 6000 pounds per square inch) in the oil line.

The nozzle support has a passage 102 leading to an opening 103 in the side of the tube 92, and a passage 104 leading to a groove 105 130

extending upwardly on the opposite side of the tube. These passages are closed adjacent the tube 92 by two plugs 106, 107. Since the cap 98 is closed tight any fuel oil escaping from the nozzle is forced back through the groove 105 and passage 104 to a suitable overflow receptacle.

In order to protect the apparatus from excessive pressures the nozzle support has a 10 threaded opening to receive a hollow set screw 108 which holds a spring 109 in engagement with a disk 110 having a stem 111 extending upwardly therefrom. This disk 110 bears on a small ball 112. The spring 15 109 is arranged to be stiff enough to require about twice the nozzle pressure to open it so that it will allow the oil to by-pass to the passage 104. The connecting passage from the passage 104 to the chamber containing 20 the valve 112 is made by drilling a hole 113 which is closed by the plug 114. The spring 109 is adjusted with the screw 108'.

The nozzle is held in place by means of the stud 115 and nut 116. A set screw 115' 25 prevents the nozzle holding block from tilting when the cap 116 is tightened. A bushing 95' at the end of the nozzle holds the stem 95 aligned, the fuel passing through the four grooves shown in Figure 5^a.

30 The operation of this apparatus is as follows: It is assumed that the cam 56 will be rotated once in exactly two revolutions of the engine crank shaft when this apparatus is applied to a four-cycle engine, although it 35 may be equally well applied to a two-cycle engine, but in any event the cam 56 determines the timing of the charge, and it will be seen from the development of a portion of that cam adjacent the rise 57 how the regulation is accomplished.

In the ordinary running of the engine the fuel will be ejected from one end to the other of the arrow *a*. The cams 52 and 53 are arranged so as to permit the valve 66 to 45 close earlier to the extent of the distance between the vertical lines at the space indicated at *b*.

In order to provide for additional power, it is possible to adjust the cam 52 so as to 50 delay the cut-off as much as is indicated by the space between the vertical lines at *c*, and in the event of an exceedingly heavy load the cut-off may be even delayed as long as 55 the space between the two lines as indicated at *d*. This change in the time of admission and cut-off is effected by the advance closing or delayed opening of the valve 66, and the increased fuel feed is represented by the 60 space between the horizontal lines at *e*, *f* and *g*.

As the cam 56 is rotated the slide 81 will rise and fall, its fall being insured by the operation of the spring 84 which pushes it down upon the cam. As it rises the oil in 65 the block 15 will be pushed back into the

feed pipe until the moment when the cams 52, 53 permit the valve 66 to seat. This will then allow the flange 68 on the valve to prevent the oil from having access to the center of the valve, thereby placing the pressure directly upon the oil in the chamber and upon the valve 79 which will force it into the pipe 77 leading to the spray nozzle. Thereupon the pressure will cause the stem 95 to rise when it becomes sufficiently high to 70 lift the spring 98. This lift is an exceedingly small amount, for it is aimed to run the pressure on the oil in the feed pipe up to several thousand pounds, in order to produce a smoked-like spray. This stem will be 75 lifted by reason of the fact that its upper portion is slightly larger than its lower portion, the differential thus produced being sufficient to allow the stem to rise, retarded however, by the pressure of the spring 98 80 above mentioned.

While the stud 115 holds the nozzle carrying block in place, the set screw 115' will prevent the block from tilting, and thereby produce a gas-tight joint at the opening 90 where the nozzle enters the engine. Since small particles of dirt or other objects impossible to pass through the nozzle might get into the oil, a relief valve is provided in the valve 112 which is held down by the 95 spring bearing upon the washer 110. This will permit the oil to by-pass back into the passageway 104 without injury to the apparatus, and in the same way any oil that escapes from the top of the bushing 96 surrounding the upper portion of the valve stem 95 will by-pass into the passageway 104, and a cup or small receptacle therefor will be formed to catch the drip.

A particular advantage of the type of 105 governor illustrated herein lies in the fact that the angle of rise of the weights 18 and 19 may be altered for different speeds, thereby always maintaining a very close regulation of the engine, since as the position of 110 the weight supporting arm is varied, the direction of movement of the weights is altered to such an extent as to make it possible to increase or diminish the tendency of the weights to return to their normal 115 position, as may be desired for different speeds.

What I claim is as follows, but various modifications may be made in the construction shown in the drawings and above particularly described form, within the purview of my invention:

1. A fuel regulator for explosion engines comprising a time shaft having a cam thereon, a fuel pump operated by said cam, supply and discharge pipes extending to said pump, a pair of cams for seating and unseating a valve of said pump, manual means for shifting one of the cams, and a centrifugal governor for shifting the other of said 125 130

cams to determine the timing of the fuel injection.

2. A fuel regulator for explosion engines comprising a time shaft carrying a cam, a fuel pump operated by said cam, supply and discharge pipes extending to said pump, a pair of cams for seating and unseating a valve of the pump to cause the delivery of a charge of oil therefrom, manually operated means to rotate one of the cams, and a centrifugal governor to rotate the other cam to determine the timing and duration of the oil injection period.
3. A fuel regulator for explosion engines comprising a time shaft, a cam carried thereby, an oil pump operated by said cam, supply and discharge pipes extending to said oil pump, a pair of cams for seating and unseating a valve of the pump to cause the delivery of a charge of fuel therefrom, a sleeve vertically slidable on the axis of the

time shaft for rotating one of the cams, a centrifugal governor, links extending from the centrifugal governor to said sleeve whereby the position of the governor is altered, and means whereby the other cam is rotated by the operation of the governor whereby the timing and duration of the oil feed to the engine is regulated.

4. A fuel regulator for explosion engines comprising a time shaft, a cam carried thereby, a fuel injection pump operated by the cam, means to seat and unseat a valve of the pump to increase or diminish the period of injection of the fuel, a pivoted weight governor operated by the cam shaft, and manual means for varying the position of the pivots of the weights to vary the timing of the fuel injection.

In testimony whereof I have hereunto set my hand this 4th day of May, A. D. 1922.

MOYES J. MURPHY.
